UNITED STATES PATENT OFFICE.

STEPHEN M. HAMBLIN, OF STOUGHTON, MASSACHUSETTS; ASSIGNOR TO BAY STATE LAST COMPANY, OF STOUGHTON, MASSACHUSETTS, A CORPORATION OF MASSACHUSETTS.

LAST.

No. 877,995.

Specification of Letters Patent.

Patented Feb. 4, 1908.

Application filed August 15, 1907. Serial No. 388,619.

To all whom it may concern:

Be it known that I, STEPHEN M. HAMBLIN, a citizen of the United States, residing at Stoughton, in the county of Norfolk, State of Massachusetts, have invented a certain new and useful Improvement in Lasts, of which the following is a specification, reference being had therein to the accompanying drawings.

10 The invention has relation to divided or hinged lasts and forms, and consists in a last or form of this class, of improved and novel construction, which I will explain with reference to the drawings, in which latter,—
15 Figure 1 is a view in side elevation of a last or form embodying the invention. Fig. 2 is a view showing the same in longitudinal vertical section.

Having reference to the drawings:—The 20 fore-part of the last or form shown therein is designated 1, and 2 is the heel-part. The fore-part is formed with the transverse socket 3, the shank extension 4 projecting rearwardly from below the said socket, and the surface 5 25 constituting an extended bearing at the top of the said extension. The heel-part 2 is formed with a forwardly-projecting extension having the integral roll 5 at the forward end thereof, the neck 6 behind such roll, and 30 the surface 7 constituting an extended bearing at the under side of the said extension.

The roll 3 is cylindrical in cross-section, except, of course, at its juncture with the neck, and the socket 5 is similarly shaped. The 35 said socket incloses more than one-half of the circumference of the roll, the remaining portion of such circumference being sufficient to permit the required extent of swinging movement of the two members with relation 40 to each other.

The fore-part and heel-part constitute, primarily, integral portions of the same piece or block, the latter having given to it the required external shape of the last or form to 45 be produced. They are divided from each other, by means of a thin saw, along the line *a, b*, Fig. 1, the cut extending transversely through the thickness of the piece or block and enabling the two members to be separated from each other.

The members having been separated, as by a transverse movement, a hole 8, Fig. 2, is made through the roll 3 and neck 6, at or near midwidth of the last or form, and a notch or

groove 9 is made in the front side of the roll. 55 The parts then are fitted together again, and are subjected to pressure within a clamp, whereby the upper side of the socket is closed down upon the top of the roll. While held in this condition, holes are bored through the 60 last or form, and the pins or dowels 10, 11, are driven tightly into such holes and secured in place in the fore-part. Dowel 11 serves to hold the top and bottom of the socket closed firmly upon the roll. The two dowels prevent the fore-part from splitting at the 65 socket. In addition, by their engagement with the roll they prevent lateral displacement of the fore-part and rear-part with relation to each other. 70

The bearing 5 is tangential with relation to the cylindrical wall of the socket and uniform, or substantially so; that is to say, it has no abrupt changing of direction or angles. Bearing 7 is tangential with relation to the 75 cylindrical exterior of the roll, and also uniform, or substantially so. Consequently, all of the roll is above the said bearings, and the underside of the neck is in direct line with the underside of the roll. When the 80 fore-part and heel-part are put together, the bearing 7 rests fairly upon the bearing 5, and all of the looseness or play between the exterior of the roll and the interior of the socket locates itself at the top of the roll. When, 85 now, the pressure is applied, the lip constituted by the extreme rear end of the instep portion is sprung thereby downward and rearwardly around the roll so as to close the socket upon the latter. The socket is held 90 by means of the dowel 11 in closed condition, clasping the roll with any desired degree of pressure, so as to secure the required amount of friction to prevent the two parts of the last or form from moving too easily upon 95 each other.

By making the roll 5 integral with the neck 6 of the forward extension of the heel-part, greater strength and durability are secured than would be if the roll was formed as 100 a separate piece and fastened to the said neck.

What is claimed as the invention is,—

In a divided or hinged last or form, in combination, the heel-part constructed with the 105 forward extension formed with the integral roll and the uniform bearing tangential to the said roll; the fore-part constructed with

the cylindrical transverse socket receiving the said roll and clasping more than one-half the circumference of the latter, the shank-extension projecting rearward of the said socket, and the uniform bearing tangential to the socket; and the dowel inserted in the instep-portion and shank-extension of the fore-part, passing through a hole in the roll,

and holding the socket contracted upon the roll. 10

In testimony whereof I affix my signature in presence of two witnesses.

STEPHEN M. HAMBLIN.
